COMBINATION SPOTTING BOARD STAND,
VACUUM CONTROL, AND CONDENSING
CHAMBERGlen C. Shoop and Frank G. Hoover,
Escondido, Calif.

Application December 28, 1946, Serial No. 719,006

15 Claims. (Cl. 68—6)

1

Our invention relates to a combination spotting board stand, vacuum control and condensing chamber and the objects of our invention are:

First, to provide a spotting board for spotting fabric or the like with which is connected a vacuum tube around which the steam chamber forms a steam condenser which automatically produces wet steam for use in spotting articles on said spotting board;

Second, to provide a spotting board and vacuum control of this class which is provided with control means which continually draws vacuum through the board and cools a steam condenser associated therewith, whereby use of wet steam from said condenser is compensated for by the condensate created around the vacuum tube passing through said condenser;

Third, to provide a combination spotting board stand and vacuum control and condensing chamber of this class in which a single foot control progressively operates the vacuum drawn through the spotting board, then releases dry steam to the spotting gun operated in conjunction therewith and then releases wet steam to said spotting gun by simply moving the foot pedal downwardly in one direction;

Fourth, to provide a combination spotting board stand and vacuum control of this class in which the suction leg arranged to conduct the vacuum supports the spotting board on its upper end and communicates with a sump at its lower end which is arranged to receive lint and other deleterious matter from the clothing as well as solvent or the like;

Fifth, to provide a spotting board of this class in which the vacuum conductor therein is constructed of sheet metal and forms part of the spotting board structure;

Sixth, to provide a spotting board of this class having novel garments supporting means in connection therewith for holding garments and preventing the same from overhanging said spotting board and reaching the floor during spotting operations being done on said clothing; and

Seventh, to provide a combination spotting board stand, vacuum control and condensing chamber of this class which is very simple and economical of construction in accordance with its utility, efficient in its action and which will not readily deteriorate or get out of order.

With these and other objects in view, as will appear hereinafter, our invention consists of certain novel features of construction, combination and arrangement of parts and portions as will be hereinafter described in detail and particularly

2

set forth in the appended claims, reference being had to the accompanying drawings and to the characters of reference thereon forming a part of this application in which:

Fig. 1 is a side elevational view of our combination spotting board stand, vacuum control and condensing chamber showing portions thereof broken away and in section to amplify the illustration and showing by arrows the flow of vacuum therethrough; and Fig. 2 is an end elevational view therefrom showing by arrows and legends the flow of steam and drainage to and from the condensing chamber thereof; Fig. 3 is a fragmentary side elevational view of the spotting board of our combination spotting board stand, vacuum control and condensing chamber showing portions thereof broken away and in section to amplify the illustration; Fig. 4 is a plan view thereof showing portions broken away and in section to amplify the illustration; and Fig. 5 is a sectional view taken from the line 5—5 of Fig. 4.

Similar characters of reference refer to similar parts and portions throughout the several views of the drawings.

The spotting board 1, vacuum channel 2, suction leg 3, sump 4, condenser 5, vacuum control valve 6, valve control links 7, 8, 9 and 10, steam valve 11 and hot water valve 12, levers 13, 14, 15, 16 and 17, shaft 18, foot pedal 19, spotting gun 20 and garment support 21 constitute the principal parts and portions of our combination spotting board stand, vacuum control and condensing chamber.

The spotting board 1 as shown best in Figs. 3, 4 and 5 is provided with a glass top 1a and a screen 1b adjacent the glass top 1a outlined by frame 1c beneath which the open end of the vacuum channel 2 is positioned as shown in Figs. 3 and 4 of the drawings, the open end 2a of this vacuum channel 2 is defined by a substantially cylindrical portion 2b extending into close proximity to the screen 1b concentrating the vacuum drawn upon a confined portion of the screen 1b. As shown in cross section in Fig. 5, the spotting board is composed of two channels 1d and 1e. The channel 1d forms the bottom of the spotting board and extends upwardly at the sides thereof retaining opposite edge portions 1f of the glass top 1a. The channel member 1e fits inside the channel 1d and the uppermost portion 1g of the channel 1e is below the uppermost portions of the channel 1d at opposite edges 1f of the glass top member 1a, thus the glass top member 1a is completely supported intermediate opposite legs of the channel 1d which retains the

same in position. It will be here noted that the vacuum channel 2 is an inverted channel and that the lower side 1h of the channel 1d forms the lower side of the vacuum channel 2 as shown best in Fig. 5 of the drawing. The upper end of the suction leg 3 is provided with a flange 3a which is secured to the lower side 1h of the channel 1d around the opening 1j in said lower side 1h of said channel 1d. This suction leg 3 is a hollow cylindrical member and communicates with the interior of the vacuum channel 2 and also supports the spotting board 1 all as shown best in Figs. 1 and 4 of the drawings. The lower end of the suction leg 3 is supported on the sump 4 in communicative relation with the interior thereof as indicated by arrows in Fig. 1 of the drawings. This sump 4 is preferably a hollow cylindrical member and secured in communicative relationship with the upper side thereof adjacent the suction leg 3 is the condenser 5 which is composed of an inner vacuum connecting tube portion 5a and an outer casing portion 5b intermediate which steam is stored. Steam is supplied to the condenser 5 intermediate the vacuum conducting tube 5a and casing portion 5b by means of the steam inlet 5c communicating with a conventional steam boiler not shown in the drawings. This steam inlet 5c is arranged in communicative relation with the casing portion 5b above the liquid level therein. The drain tube 5d communicates with the interior of the casing portion 5b and is arranged to drain hot water backwardly into the steam boiler by the process of gravitation, it being noted that the drain tube 5d is positioned considerably below the steam inlet tube 5c. Communicative with the normally upper end of the vacuum conductor tube 5a of the condenser 5 is the vacuum control valve 6. This vacuum control valve 6 is a conventional butterfly valve having a bell crank lever 13 secured on the axle 6a thereof which is pivotally connected to the link 7. The steam valve 11 communicates with the interior of the casing portion 5b of the condenser 5 above the liquid level therein and is provided with an outlet tube 11a communicating with the T 11b communicating with the hot water valve 12 the outlet of which is regulated by a smaller valve 12a which communicates directly with the T 11b, having a spotting gun outlet tube 11c which is a flexible tube connected to the spotting gun 20. It will be noted that the hot water valve 12 communicates with the interior of the casing portion 5b below the liquid level therein and is arranged to conduct hot water to the T 11b thence to the spotting gun 20. The upper end of the link 7 is connected to the lever 13 in pivotal relation therewith and the lower end of said link 7 is pivotally connected to the lever 14 arranged to operate the steam valve 11. Pivotally connected at its upper end to the lever 14 is the link 8. The lower end of this link 8 is longitudinally adjustably connected with the lever 15 which is pivotally mounted on a pin 15a stationarily connected to the casing portion 5b of the condenser 5. The opposite end of this lever 15 is pivotally connected to the link 10 which is pivotally connected at its lower end to the lever 17 fixed on the end of the shaft 18 at the opposite end from the foot pedal 19 it being noted that the shaft 18 is supported by bearings 18a on the base 4a of the sump 4. The link 9 is longitudinally adjustably connected at its upper end to the lever 15 and is pivotally connected at its lower end to the lever 16 which is operatively engaged with the hot water valve 12.

The operation of our combination spotting board stand, vacuum control and condensing chamber is substantially as follows:

When it is desired to pull vacuum through the spotting board, and screen on the spotting board 1, the operator presses downwardly on the foot pedal 19 rotating the shaft 18 and pivoting the lever 17 having the link 10 in connection therewith. The lever 15 is pivoted on the pin 15a and the links 7 and 8 are forced downwardly as shown in Fig. 2 of the drawings opening the butterfly of the vacuum control valve 6. The vacuum drawn through the tubular portion 5a of the condenser 5 passes from the screen 1b through the vacuum channel 2 through the suction leg 3 downwardly through the sump 4 and upwardly in said tubular portion 5a concentrically positioned in the casing 5b of the condenser 5. When this air passes through the tubular portion 5a of the condenser 5 due to vacuum in the tube 5a, the steam surrounding said tube 5a above the liquid level is condensed whereby the liquid level in the casing 5b of the condenser 5 is maintained substantially at the drain tube 5d from which excess water gravitates to a conventional steam boiler not shown in the drawings. When the operator forces the foot pedal 19 downwardly still further, the steam valve 11 is opened causing dry steam to pass from the casing portion 5b of the condenser 5 above the liquid level therein outwardly through the tube 11a to the spotting gun tube 11c and thence to the spotting gun 20 which may be used in operating on fabric placed over the screen 1b of the spotting board 1. When it is desired to force hot water through the spotting gun 20, the operator progressively forces the foot pedal 19 downwardly still further whereupon the link 9 in connection with the levers 15 and 16 opens the hot water valve 12, communicating with the interior of the casing portion 5b of the condenser 5 below the liquid level therein. When the hot water passes through the valve 12 and the valve 12a into the tube 11c in connection with the spotting gun 20, the proportion of hot water to the proportion of dry steam passing from the valve 11 may be regulated by setting the small valve 12a. This small valve 12a may be used to restrict the flow of hot water from the hot water valve 12 so that the operator may control the amount of moisture in the steam as desired which is being issued from the spotting gun 20. It will be here noted that a considerable quantity of wet steam may be used without unduly depleting the supply thereof in the casing portion 5b of the condenser 5 because continual condensation of dry steam in the upper portion of the casing 5b is accomplished by the flow of vacuum through the tube 5a as indicated by arrows in Fig. 1 of the drawings.

Though we have shown and described a particular construction, combination and arrangement of parts and portions, we do not wish to be limited to this particular construction but desire to include in the scope of our invention the construction, combination and arrangement substantially as set forth in the appended claims.

Having thus described our invention what we claim as new and desire to secure by Letters Patent is:

1. A spotting board having a foraminous work supporting surface, a vacuum tube having an intake aperture beneath said surface to create suction therethrough, a steam condenser comprising inner and outer casing members having a reservoir therebetween, means for conducting vacuum

from the interior of said vacuum tube through the inner casing of said condenser for cooling steam in said reservoir.

2. A spotting board having a foraminous work supporting surface, a vacuum tube having an intake aperture beneath said surface to create suction therethrough, a steam condenser comprising inner and outer casing members having a reservoir therebetween, means for conducting vacuum from the interior of said vacuum tube through the inner casing of said condenser for cooling steam in said reservoir, valve means at the vacuum conducting outlet end of said inner casing for shutting off the passage of air through said spotting board, vacuum tube and said inner casing of said condenser.

3. A spotting board having a foraminous work supporting surface, a vacuum tube having an intake aperture beneath said surface to create suction therethrough, a steam condenser comprising inner and outer casing members having a reservoir therebetween, means for conducting vacuum from the interior of said vacuum tube through the inner casing of said condenser for cooling steam in said reservoir, valve means at the vacuum conducting outlet end of said inner casing for shutting off the passage of air through said spotting board, vacuum tube and said inner casing of said condenser, a boiler drain tube connected with said condenser and communicating with the interior of said reservoir between said inner and outer casings, and disposed intermediate the upper and lower ends of said condenser for establishing a predetermined level of liquid in said reservoir.

4. A spotting board having a foraminous work supporting surface, a vacuum tube having an intake aperture beneath said surface to create suction therethrough, a steam condenser comprising inner and outer casing members having a reservoir therebetween, means for conducting vacuum from the interior of said vacuum tube through the inner casing of said condenser for cooling steam in said reservoir, valve means at the vacuum conducting outlet end of said inner casing for shutting off the passage of air through said spotting board, vacuum tube and said inner casing of said condenser, a boiler drain tube connected with said condenser and communicating with the interior of said reservoir between said inner and outer casings, and disposed intermediate the upper and lower ends of said condenser for establishing a predetermined level of liquid in said reservoir, a steam outlet tube communicating with the interior of said outer casing of said condenser above said boiler drain tube, and a water conducting tube communicating with the interior of said outer casing and said reservoir below said boiler drain tube.

5. A spotting board having a foraminous work supporting surface, a vacuum tube having an intake aperture beneath said surface to create suction therethrough, a steam condenser comprising inner and outer casing members having a reservoir therebetween, means for conducting vacuum from the interior of said vacuum tube through the inner casing of said condenser for cooling steam in said reservoir, valve means at the vacuum conducting outlet end of said inner casing for shutting off the passage of air through said spotting board, vacuum tube and said inner casing of said condenser, a boiler drain tube connected with said condenser and communicating with the interior of said reservoir between said inner and outer casings, and disposed intermediate the upper and lower ends of said condenser for establishing a predetermined level of liquid in said reservoir.

diate the upper and lower ends of said condenser for establishing a predetermined level of liquid in said reservoir, a steam outlet tube communicating with the interior of said outer casing of said condenser above said boiler drain tube, and a water conducting tube communicating with the interior of said outer casing and said reservoir below said boiler drain tube, valves for said steam tube and said water tube.

6. A spotting board having a foraminous work supporting surface, a vacuum conducting channel having an intake aperture beneath said surface to create suction therethrough, a hollow tubular vacuum conductor communicating with the interior of said channel, a sump in which the opposite end of said hollow tubular vacuum conductor communicates, a condenser having an internal vacuum conducting tube opening at its lower end into said sump.

7. A spotting board having a foraminous work supporting surface, a vacuum conducting channel having an intake aperture beneath said surface to create suction therethrough, a hollow tubular vacuum conductor communicating with the interior of said channel, a sump in which the opposite end of said hollow tubular vacuum conductor communicates, a condenser having an internal vacuum conducting tube opening at its lower end into said sump, a valve communicating with the interior of said internal vacuum conducting passage of said condenser, at the opposite end thereof from said sump.

8. A spotting board having a foraminous work supporting surface, a vacuum tube having an intake aperture beneath said surface to create suction therethrough, a steam condenser having a passage therethrough communicating with the interior of said vacuum tube, means to supply steam to the condenser and means to convey steam and condensate therefrom, and boiler return means for maintaining a liquid level intermediate the upper and lower ends of said condenser.

9. A spotting board having a foraminous work supporting surface, a vacuum tube having an intake aperture beneath said surface to create suction therethrough, a steam condenser having a passage therethrough communicating with the interior of said vacuum tube, overflow means for maintaining a predetermined fixed liquid level intermediate the upper and lower ends of said condenser, and steam and water outlet valves communicating with the interior of said condenser above and below the fixed liquid level therein respectively.

10. A spotting board having a foraminous work supporting surface, a vacuum tube having an intake aperture beneath said surface to create suction therethrough, a steam condenser having a passage therethrough communicating with the interior of said vacuum tube, overflow means for maintaining a predetermined fixed liquid level intermediate the upper and lower ends of said condenser, steam and water outlet valves communicating with the interior of said condenser above and below the fixed liquid level therein respectively, and a control valve at the outlet end of said passage and communicating with the interior thereof.

11. A spotting board having a foraminous work supporting surface, a vacuum tube having an intake aperture beneath said surface to create suction therethrough, a steam condenser having a passage therethrough communicating with the interior of said vacuum tube, means for main-

taining a predetermined fixed liquid level intermediate the upper and lower ends of said condenser, steam and water outlet valves communicating with the interior of said condenser above and below the fixed liquid level therein respectively, a control valve at the outlet end of said passage and communicating with the interior thereof, and control means for said steam and water valves and said control valve for progressively operating same.

12. A spotting board having a foraminous work supporting surface, a vacuum tube having an intake aperture beneath said surface to create suction therethrough, a steam condenser having a passage therethrough communicating with the interior of said vacuum tube, means for maintaining a predetermined fixed liquid level intermediate the upper and lower ends of said condenser, steam and water outlet valves communicating with the interior of said condenser above and below the fixed liquid level therein respectively, a control valve at the outlet end of said passage and communicating with the interior thereof, and control means for said steam and water valves and said control valve, for progressively operating same by first opening said vacuum control valve, then opening said steam valve above the liquid level in said condenser, and then opening the said water valve below the liquid level in said condenser.

13. A spotting board having a foraminous work supporting surface, a vacuum conducting channel having an intake aperture beneath said surface to create suction therethrough, a hollow cylindrical suction leg communicating with said vacuum conducting channel and supporting said spotting board, a sump communicating with the interior of the normally lower end of said suction leg, a condenser thermally connected with said sump including a centrally disposed vacuum conducting tube opening into said sump.

14. A spotting board having a foraminous work supporting surface, a vacuum conducting channel having an intake aperture beneath said surface to create suction therethrough, a hollow cylindrical suction leg communicating with the

interior of said vacuum conducting channel and supporting said spotting board, a sump communicating with the interior of the normally lower end of said suction leg, a condenser communicating with said sump including a centrally disposed vacuum conducting tube opening into said sump, said condenser having a liquid drain tube thermally connected with the interior thereof outwardly of said vacuum conducting tube intermediate the upper and lower ends of said condenser.

15. A spotting board having a foraminous work supporting surface, a vacuum conducting channel having an intake aperture beneath said surface to create suction therethrough, a hollow cylindrical suction leg communicating with the interior of said vacuum conducting channel and supporting said spotting board, a sump communicating with the interior of the normally lower end of said suction leg, a condenser thermally connected with said sump including a centrally disposed vacuum conducting tube opening into said sump, said condenser having a liquid drain tube communicating with the interior thereof outwardly of said vacuum conducting tube intermediate the upper and lower ends of said condenser, said condenser being provided with a steam inlet tube above said drain tube.
